UNITED STATES PATENT OFFICE.

HARRY L. VAN ZILE, OF NEW YORK, N. Y.

WIND-DEFLECTOR.

1,071,280.

Specification of Letters Patent.

Patented Aug. 26, 1913.

Application filed August 21, 1912. Serial No. 716,234.

To all whom it may concern:

Be it known that I, HARRY L. VAN ZILE, a citizen of the United States, and resident of the borough of Manhattan, in the county 5 of New York and State of New York, have invented certain new and useful Improvements in Wind-Deflectors, of which the following is a specification.

This invention relates to a device for deflecting currents of air or other fluids.

One of the objects of the invention is the production of a deflector which will collect and subdivide into strata a portion of the encountered current and to conduct these 15 strata against another portion of the same current at a different level in such a manner that the strata will assist each other in imparting the maximum deviation from its course to the latter portion of said current, 20 so as to obtain the largest zone of quiescent medium in rear of the deflected currents.

Another object is to provide a deflector wherein the stratified currents are received tangentially to the direction of movement, 25 and are protected from frictionally interfering with each other by internal impingement, during their travel from entrance to exit.

A further object is to provide a deflector 30 wherein the exits of the deflected current strata terminate in the same plane substantially parallel to the direction of movement in order that the outflowing currents may reinforce each other and thus maintain their 35 velocity as long as possible so as to deflect the intersected portion of the current to the maximum distance from the deflector.

A still further object is to provide a deflector the location of which is within the 40 projected vertical cross-sectional area of a vehicle and below the line of sight of the driver so as not to add to the air resistance.

Still another object is to provide a deflector wherein the subdivided currents issue 45 forwardly so that the deflecting and deflected currents change their direction and move rearwardly at a level as far away as possible from a person behind the deflector.

A further object is to provide a simple 50 and economical deflector constructed in a durable manner which can be collapsed to occupy the minimum space when not in use, and also adjusted into desired position.

Other objects and advantages will become 55 apparent as the description proceeds.

Devices heretofore in use for protecting the occupants of an automobile from excessive wind pressure or dust, have been constructed with a view of either pushing the air in front of them, as in the case of the 60 conventional glass-shield; or with the purpose of making the wind slide up on a curved surface or an inclined plane to pass over the heads of the people seated in the car, as used for instance in hoods of various 65 shapes. In the former case, not only an excessive resistance is developed which impedes the speed of the car, but eddies are also created that cause the side currents to close in with increased force on the persons seated in rear of the front or driver's seat. Moreover the fragile nature of glass makes it always a source of danger and severe accidents have happened when automobiles have been brought to a sudden stop, causing the 70 occupants to be thrown against or through the glass front. With hoods the sliding effect is very much reduced because the wind or air currents spread out sidewise particularly if the hood is prow-shaped. For this 75 reason it has been customary to carry the edge of the hood up in line with the operator's eyes and to construct the portion below of celluloid. Through usage this 80 material soon becomes opaque and deteriorates 85 in time until it eventually breaks up. In some instances the upper edge of the hood has been given a reversed curve with the object of deflecting the encountered air current, but due to the fact that this curved 90 portion has been left exposed, higher streams or currents have impinged directly on the current being deflected so much so as to reduce its velocity so that it was simply forced rearwardly over the edge back into 95 the chauffeur's face.

By the design of the present invention a wind or current deflector avoiding the hereinbefore mentioned objections is produced. In its preferred embodiment the device 100 under consideration comprises a number of curved vanes of progressively increasing lengths associated with angular side pieces in such a manner that a wedgelike structure is produced, through which a plurality of 105 passages having gradual bends are formed, and furthermore the arrangement of these passages is such that they receive the encountered current tangentially at their entrances which are in offset relation to each 110

other. The subdivided currents or strata are protected from each other and from the main body of the air encountered by the deflector, and issue in a forward direction through exits disposed in the same plane. The device may be adjusted in its entirety for the purpose of meeting different conditions or may have its volume changed.

By preference the invention is applied to usage in connection with automobiles but it is understood that no limitation either to its application or its exact specific form is intended. It is obvious that the invention is adapted for any purpose where it is required to deflect one portion of a current upon another to effect a quiescent zone directly in rear thereof.

In the drawings hereto annexed: Figure 1 is a front view of the invention applied to the head of a person. Fig. 2 is a side view of Fig. 1, parts being shown in section. Fig. 3 is a fragmentary plan view of a collapsible deflector, extended. Fig. 4 is a section on the line 4—4 of Fig. 3. Fig. 5 is a view similar to Fig. 4, showing the deflector collapsed. Fig. 6 is a diagrammatic sectional view of the deflector showing the action between the air currents. Fig. 7 is a fragmentary plan view of an automobile showing a modification of the deflector. Fig. 8 is a plan view of a detached deflector of another modified form, and Fig. 9 is a section on the line 9—9 of Fig. 8.

In these views the numeral 10 represents curved vanes or shields which are spaced a certain distance apart so that a plurality of passages 11 having gradual bends are formed between them. These vanes are of variform but similar nature and are arranged in such a manner that the shortest and sharpest curved passage first encounters the air currents or winds with the adjacent passages disposed serially, one after the other in order, according to sizes or lengths. The entrances 12 to said passages are tangential to the currents so as to collect the maximum amount thereof and to deflect the strata gradually, and they may be either above or below the exits 13 as Figs. 2 and 50 4 or 6 respectively represent. In the preferred form of the invention the vanes or partitions 10 between the passages, at the entrances of the latter, are offset back of one another and at different levels at "a" Fig. 6 to reduce the length of the passages to a minimum. By the segregation or formation of air strata currents, the internal friction of the air particles traveling in a path of constantly changing direction is lessened, eddying is reduced, and the air being deflected in the deflector, is protected from the main body of incoming air which impinges against the deflector and is split up in separate streams. Thus, only a negligible portion of the air traveling through

each passage is subject to lateral pressure and consequent disturbance and internal friction by the main body of encountered incoming air. This traveling stratum is represented by the shaded area in Fig. 6 being included between the lower edge of one vane and the horizontal line "b" drawn from the lower edge of the adjacent vane. In other words, the air being deflected in the deflector is protected and allowed to develop its maximum velocity in the new direction in which it issues from the exits of the passages. The energy of the air due either to its own velocity or to the speed of the moving vehicle is thereby utilized to the best advantage. The passage of the air between the gradually curved vanes merely changes its direction, while its initial velocity is maintained as nearly as possible the same from entrance to exit, less of course the skin friction of the said vanes.

It will be understood that the vanes should not be placed too close together, and conversely that they should not be placed too far apart. In one case skin friction would become excessive, in the other case internal friction and lateral pressure would be unduly increased. I have found that vanes spaced about $\frac{1}{2}$ " apart for the head deflector and 1" apart for the vehicle deflector have given satisfactory results. This spacing has of course to be proportioned according to the amount of air handled.

The different passages have their exits terminating in the same plane and issue preferably forwardly, by virtue of which the forces of the outflowing currents support one another and collectively maintain the maximum velocity, and as they are conducted angularly against another portion of the same current moving at a different level, this latter portion will have its direction changed as far forward as possible and it will be given the greatest deviation from its course in order to obtain a quiescent zone of maximum dimensions in the rear of the deflector.

In their preferred embodiments the said vanes 10 are composed of circular arcs whose centers are located on a line "c" median between the lines marked respectively "d" and "e" of the entrances and exits of the passages 11 (Fig. 6). The vertical distance "f" on the line "c" from the center of the arc of each vane to the line or plane of the exits "e" is considerably less than the distance "g" from the same center to a line "h" parallel with "e" and tangent to the lower edge of the vane. Fig. 6 illustrates this fact in connection with the rear-most vane. By this construction the intake portion of the air stratum moving between each pair of vanes below a horizontal line "i" will have a larger leverage "g" than that of the outgoing portion "f". Also due

to this preponderance of the intake column which is constantly acted upon by the air current flowing into the mouth or entrance 12 of the passage 11 there is less loss of velocity head of each current stratum, than if the intake and outgoing columns were nearer equal. In fact, the least loss of velocity head exists with an intake radius of 1 to an outlet of 0, such as for instance is illustrated in Fig. 9. When this construction is used the turning of the air currents takes place farther back than with the type of deflector shown by the diagram in Fig. 6.

The deflector represented in Figs. 1 and 15 2 is for use in connection with the head or headgear of a chauffeur or aviator, to deflect the wind away from the eyes of the person. Here the intake is above the plane of issuance of the current strata. A strap 20 18 serves to fasten the device in position, the space 19 between the last vane and the person's head being occupied by a pad or other means of similar nature which renders the device comfortable to the wearer. Where it 25 is deemed expedient a shield or collector 20 may be employed to increase the wind catching surface of the deflector.

The construction shown in Figs. 3, 4 and 30 5 represents a device wherein the vanes are collapsible into each other so as to occupy the smallest space possible when not in use. The vanes are here provided at each end with slides 25 having tail portions 26 secured thereto. These slides run in guides 35 27 formed on front side-pieces 28 which are hinged at 38 to rear side-pieces 29 fixed to the last or largest vane. The length of slide includes three vanes but is only fastened to one of them except the two outer ones which 40 are secured to the same slide, because they come within the rear side pieces 29 when the front side-pieces 28 are folded inwardly over the collapsed vanes (Fig. 5). For the sake of simplicity only one half of each side 45 piece is shown as having slides and guides but it will be understood that the latter will be provided on both sides of the center line of the vanes to obtain proper alinement. In order that the slides may engage and operate each other when the vanes are pulled 50 out or pushed in, they are provided with dogs and abutments 30 and 31 respectively. The dog of one slide operates between an abutment and a dog on the adjacent slide 55 so as to move the latter forward and back. The vanes are also provided with resilient ears 32 which wedgingly engage flanges 33 on the edges of the front side pieces 28, when the said vanes are in their extended 60 position to hold them from rattling. As shown, the forward vane of the deflector is provided with a bar 34 having its ends beveled as at 35. These beveled portions are engaged by spring actuated plungers one of 65 which is shown at 36, which plungers tend

to draw the vanes forwardly with the ears 32 against the flanges 33. In order to prevent the front side pieces 28 from swinging outwardly, stops 37 limit their movement. The rear portion of the deflector may be 70 pivotally supported by a rod 40 carried in clamping brackets 41 formed with or attached to the dashboard 42 of the automobile or other primary support. Lugs 43 riveted to the rearmost vane, are pinned to the said rod 40 and when the latter is rocked the deflector in its entirety is brought from its position over the motor-hood 44 rearwardly so as to permit the same to be 75 opened. Handle screws 45 clamp the rod 40, in any desired position, tightly in the split brackets 41.

In Fig. 7 is illustrated a deflector having endwise projecting portions 50, 51 of different formation and provided with vertical 80 partitions 52, to subdivide and deflect encountered side currents. In this as well as previous instances the dimensions of the deflector fall within the projected area of the automobile, by virtue of which the resistance offered is considerably less than when a straight or slantwise extending body carried up to the level of the operator's eyes is pushed through the air, while at the same time the trajectory of the deflected current 85 is high enough to cause no inconvenience to the occupants of the vehicle.

Fig. 8 shows a curved deflector, applicable either to the pilot house of a vessel or to the cab or platform of a train or trolley 100 car. Fig. 9 which is a central section of the preceding figure shows the intake of each succeeding passage in advance of the intake of the passage next above and having the passage exits disposed substantially 105 right angularly relative to their entrances. This construction may be utilized when certain conditions must be harmonized as in static structures and the like.

Two or more deflectors may be used in 110 conjunction with each other. For example, two of them may be used with their exit portions disposed toward each other, that is to say, in the relation that Figs. 2 and 4 bear to each other.

Having described my invention what I desire to secure by Letters Patent and claim is:

1. A deflector having a plurality of passages of progressively increasing lengths 120 one behind another formed to subdivide a portion of the encountered or encountering current and to conduct the subdivided stream so as to issue cross-wise to another portion of the current at a different level. 125

2. A deflector comprising a plurality of gradually curved vanes one behind another forming a plurality of passages progressively increasing in lengths which subdivide into strata a portion of the encountered or 130

- encountering air, deflect the said strata and deliver them cross-wise to another portion of the current at a different level.
3. A deflector comprising a plurality of curved vanes affording strata-forming passages having entrance ends and exit ends at different levels, said vanes being disposed rearwardly of one another and formed so as to receive the air tangentially for the full depth at the entrance ends of the passages and to deliver the strata cross-wise to the air flowing past their delivery ends.
4. A deflector comprising a plurality of curved vanes of different lengths one behind another affording a plurality of strata-forming passages having their exit ends at the same level and their entrance ends at different levels.
5. A deflector comprising a plurality of curved vanes of different lengths arranged serially according to lengths constituting means for subdividing a portion of the encountered or encountering current into strata, of changing direction and for protecting said strata until they pass beyond the lines of the deflector and issue cross-wise of the portion of the current at that level.
6. A deflector comprising a plurality of vanes having differential curvature one behind the other affording a plurality of passages serially increasing in length adapted to subdivide a portion of the encountered or encountering air and to cause the resulting streams to issue cross-wise to another portion of the air current at a different level, the exit portion of said passages being arranged to direct the issuing streams forward.
7. A deflector comprising a plurality of curved vanes one behind the other, of progressively increasing length and decreasing curvature, said vanes affording a plurality of variform passages to subdivide a portion of the encountered and encountering air and to direct it against another portion of the air current at a different level so as to cause the latter to deviate from its course.
8. A deflector, comprising a plurality of curved vanes of different lengths serially disposed rearwardly of one another according to curvature and affording a plurality of passages to subdivide a portion of the encountered or encountering air and to cause the streams to issue against another portion of the air current at a different level, said vanes being movable to receive one another for purposes of collapsing.
9. A deflector, comprising a plurality of differentially curved vanes arranged serially according to curvature affording a plurality of passages of varying lengths adapted to subdivide a portion of the encountered or encountering air and to cause the streams to issue against another portion of the cur-
- rent at a different level, means for collapsing said vanes together by moving them within one another or for opening them in spaced relation, and other means for locking them in their assigned position.
10. In a deflector, the combination of side-pieces, a plurality of curved vanes therebetween affording a plurality of deflecting passages substantially as described, and slides whereby said vanes are guided on said side pieces so as to be nested together or opened in spaced relation.
11. In a deflector, the combination of a plurality of curved vanes affording a plurality of deflecting passages substantially as described, means for guiding and supporting said vanes so as to be nested together or opened in spaced relation, and limit stops between the vanes.
12. In a deflector, the combination of a plurality of curved vanes affording a plurality of deflecting passages substantially as described, means for collapsing said vanes in nested condition, means for locking them open in spaced relation, and means for keeping them from rattling.
13. A deflector, comprising a plurality of differentially curved vanes having their centers disposed substantially on the same line, affording a plurality of variform passages for subdividing a portion of the encountered or encountering air, changing the direction of the streams, and delivering them cross-wise to another portion of the air current at a different level, and pivotal means for angularly adjusting the deflector bodily on said line of centers.
14. A reversible deflector, comprising a plurality of differentially curved vanes arranged in gradual series and affording a plurality of variform passages for subdividing a portion of the encountered or encountering air, changing the direction of the streams from their intakes and delivering them forwardly cross-wise against another portion of the air current at a level either above or below said intakes, and means for holding the device in its assigned position.
15. A deflector containing a plurality of curved passages of different lengths arranged in graduated series one behind the other and having their exit ends in the same plane, said passages subdividing one portion of the encountered or encountering current into a plurality of strata reinforcing each other and delivering them crosswise to the portion of the current at a different level from said exit ends.
16. A deflector comprising a plurality of curved vanes one behind the other affording a plurality of passages to subdivide a portion of the encountered or encountering air and cause it to issue crosswise to another portion of the air at a different level, both the entrance and exit portions of said pas-

sages being directed forward, and the intake column portion having preponderance over the exit column portion.

17. A deflector comprising a plurality of curved vanes, one behind the other affording a plurality of passages of progressively increasing length to subdivide a portion of the encountered or encountering air and cause the streams thereof to issue crosswise to a portion of the air at a different level, adjacent vanes being spaced at approximately the same distance from entrance to exit and the vanes having their entrance and exit ends respectively brought into alignment behind one another.

18. In a deflector, the combination of side members comprising fixed and hinged portions, the latter being adapted to fold inward, a plurality of vanes affording a number of deflecting passages substantially as described, and means guiding said vanes on said fixed portions so that the vanes will be nested together or opened in spaced relation between said hinged portions.

19. In a deflector, the combination of side pieces, a plurality of curved vanes therebetween affording a plurality of deflecting pas-

sages substantially as described, and means whereby said vanes are guided relatively to one another so as to be nested together or opened in spaced relation.

20. A deflector for the purposes described, composed of angular side pieces having their apices directed forward, and a wedge-like series of differentially curved vanes located between said side pieces.

21. A deflector for the purposes described, consisting of a wedgelike structure having a graduated series of through passages of curved formation.

22. A deflector for the purposes described, comprising a series of curved vanes disposed one behind another in wedgelike arrangement, side supports therefor, and flexible connections between said vanes and said supports.

Signed at the borough of Manhattan in the county of New York and State of New York this 16th day of August A. D. 1912.
